(57) **CLAIM**

The ornamental design for a roof anchor, as shown and described.

DESCRIPTION

FIG. 1 is a perspective view of a roof anchor, showing our new and original design;

FIG. 2 is a right side view of the roof anchor of FIG. 1;

FIG. 3 is a left side view of the roof anchor of FIG. 1;

FIG. 4 is a front view of the roof anchor of FIG. 1;

FIG. 5 is a rear view of the roof anchor of FIG. 1;

FIG. 6 is a top view of the roof anchor of FIG. 1; and,

FIG. 7 is a bottom view of the roof anchor of FIG. 1.

The broken lines in the figures depict portions of the roof anchor that form no part of the claimed design. The dash-dot broken lines show portions of the environment which form no part of the claim. The dot-dash broken lines represent boundaries of the claim and form no part of the claim. The drawings of the roof anchor include symbolic break and the area between both which forms no part of the claimed design. Surface shading is shown to indicate contour of the roof anchor only.
